UNITED STATES PATENT OFFICE.

FRED E. VAN HOUTEN, OF DENVER, COLORADO.

WEEDING IMPLEMENT.

1,073,188.

Specification of Letters Patent. Patented Sept. 16, 1913.

Application filed August 21, 1912. Serial No. 716,312.

To all whom it may concern:

Be it known that I, FRED E. VAN HOUTEN, a citizen of the United States, residing at Denver, in the county of Denver and State of Colorado, have invented certain new and useful Improvements in Weeding Implements, of which the following is a specification, reference being had to the accompanying drawings.

This invention relates to new and useful improvements in weeders or implements for weeding and thinning plants, the object of the invention being to provide a novel weeding implement in which the cutting blade, which is secured to the handle, can be adjusted to various angles to suit the character of the ground to be worked.

Another object of the invention is to provide a device of this character which will possess advantages in points of efficiency and durability, is inexpensive to manufacture and at the same time is simple in construction and operation.

With the above and other objects in view, the invention consists in the novel features of construction and the combination and arrangement of parts hereinafter more fully described, pointed out in the claim and shown in the accompanying drawings in which,

Figure 1 is a side elevation. Fig. 2 is a top plan view. Fig. 3 is a sectional view taken on the line 3—3 of Fig. 1.

Referring more particularly to the drawings 1 indicates the blade of the implement which is made from a strip or ribbon of suitable metal, preferably of steel and the ends thereof are bent substantially at right angles or nearly so with the body of the strip. The ends of the strip are arranged upon opposite sides of the substantially triangular plate 2 and are securely fastened thereto by means of the bolt 3 which passes through the ends of the strip and through the plate 2, and a winged nut 4 is threaded upon the end of the bolt to hold the same securely in position.

One side of the plate 2 which is substantially triangular in form is arcuate in form as shown at 5 and is provided with a plurality of semicircular recesses 6 adapted to

receive the transverse bolt or rivet 7 which extends through the openings 8 in the ends of the metal strip which forms the blade. Formed integral with one side of the plate 55 and extending downwardly at right angles therefrom is a flat shanked portion 9 which extends into an opening 10 in the end of the handle 10' and is securely fastened therein by means of the transverse bolt 11. 60

It will be readily apparent that the blade 1 may be adjusted so as to be arranged in various positions with relation to the handle by removing the nut 4 and withdrawing the bolt 3, the blade may be then adjusted and the rivet 7 arranged within one of the recesses 6, the bolt 3 being then inserted with in the openings in the ends of the strip and the winged nut 4 threaded thereon to hold the blade securely in any adjusted position. 70

The blade 1 is provided upon each side thereof with tapering cutting edges 12 which can be quickly and easily sharpened by filing or by the use of any other similar instrument so that the blade may be kept in a 75 sharpened condition at all times.

From the above description taken in connection with the accompanying drawings, it will be readily apparent that I have provided a simple and durable weeding implement wherein the blade can be adjusted to various angles with relation to the handle to suit the character of the ground which is to be worked. 80

It will also be understood that the device 85 is extremely simple in construction and can be manufactured at a comparatively low cost.

While I have shown and described the preferred form of my invention, it will be 90 obvious that various changes in the details of construction and in the proportions may be resorted to for successfully carrying my invention into practice without sacrificing any of the novel features or departing from 95 the scope of the appended claim.

What I claim is:—

In a device of the character described, the combination of a handle, having a longitudinal opening formed in one end thereof, a 100 sector plate provided with a plurality of semicircular recesses, a shank formed into

gral with said plate and arranged within the opening in the handle, a blade comprising a ribbon of metal having its ends arranged upon each side of the plate, a rivet 5 arranged transversely in the ends of the blade and adapted to be disposed within the recesses in the plate, and a bolt passing through the ends of the blade and through

the plate to securely hold the blade in various adjusted positions.

In testimony whereof I hereunto affix my signature in the presence of two witnesses.

FRED E. VAN HOUTEN.
